[57] CLAIM

The ornamental design for a refrigerator door compartment, as shown and described.

DESCRIPTION

FIG. 1 is a front, right side perspective view of a refrigerator door compartment, showing our new design. The broken lines showing other compartments and the frame of the refrigerator door are shown for environmental purposes only and form no part of the claimed design;

FIG. 2 is a left side elevational view thereof;

FIG. 3 is a front elevational view thereof;

FIG. 4 is a bottom elevational view thereof; and,

FIG. 5 is a top elevational view thereof.
